UNITED STATES PATENT OFFICE.

LESTER E. SPRAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

AUTOMATIC INTERLOCKING APPARATUS.

Application filed February 21, 1924. Serial No. 694,234.

My invention relates to automatic interlocking apparatus, and particularly to apparatus for automatically controlling traffic over conflicting routes.

5 I will describe one form of interlocking apparatus embodying my invention, and will then point out the novel features thereof in claims.

The accompanying drawing is a diagrammatic view showing one form of interlocking apparatus embodying my invention.

Referring to this drawing the reference characters *a* and *b* designate two railway tracks intersecting at a crossing A. The rails 15 1 and 1^a of track *a* are divided by means of insulated joints 2 into track sections D—E, E—F and F—G, and the rails 1 and 1^a of track *b* are similarly divided into sections H—J, J—K and K—L. The crossing A is 20 within the limits of section E—F of track *a*, and is within the limits of section J—K of track *b*. The crossing A is insulated from the rest of the tracks by insulated joints 2^a, and the rails of sections E—F and J—K are 25 made electrically continuous past the crossing by jumper wires 2^b in the usual manner. Adjacent the track section D—E is a station Z. A passing siding W is connected with section D—E of track *a* by means of a 30 switch 136.

Each track section of each track *a* and *b* is provided with a track circuit comprising a track relay designated by the reference character R with a suitable distinguishing 35 exponent connected across the rails adjacent one end of the section, and source of energy such as a track battery 3 connected across the rails adjacent the other end of each track section.

40 Eastbound traffic over track *a* is controlled by a trackway signal S^E located at point E, and west bound traffic over this track is controlled by a similar signal S^F located at point F. In similar manner northbound traffic over track *b* is controlled by signal S^J located at point J, and southbound traffic is controlled by signal S^K located at point K. These signals S may be of any suitable form and are here shown as semaphore signals 45 each capable of displaying a proceed or a stop indication. Associated with each signal S is a circuit controller designated by the reference character X with an exponent corresponding to the location. Each circuit

controller X is arranged to be closed only 55 when the associated signal indicates stop.

Each circuit controller X controls a signal repeating relay here designated by the reference character P with an appropriate exponent. For example, relay P^E is energized only when signal S^E is at stop, the circuit for this relay passing from terminal B of a suitable source of energy not shown in the drawing, through circuit controller X^E, 60 wire 6, winding of relay P^E and back to terminal C of the same source. Each of the remaining relays P is controlled by the associated signal in a manner similar to the control of relay P^E by signal S^E.

Associated also with each signal is a stick 70 relay here designated by the reference character Q with an appropriate exponent. Referring particularly to stick relay Q^E the pick up circuit for this relay passes from terminal B, through back contact 7 of track relay R', wire 8, back contact 9 of signal repeating relay P^E, wires 10 and 11, and winding of relay Q^E, back to terminal C. This circuit is closed only when relays P^E 75 and R' are de-energized. Relay Q^E is also 80 provided with a stick circuit over which current flows from terminal B, through back contact 12 of track relay R², wire 13, front contact 14 of relay Q^E, wires 15 and 11, and winding of relay Q^E back to terminal C. A 85 branch is provided for this stick circuit by means of which wire 13 may be connected to terminal B, through back contact 16 of relay R². It follows that when relay Q^E is once 90 energized this relay is maintained in its energized condition as long as either relay R² or R³ is de-energized. The control of each of the remaining stick relays Q is similar to the control of relay Q^E and will be plain 95 from the drawing.

The reference characters T and T^a designate slow acting or time element relays here shown as thermo-sensitive relays, each comprising a heating element 4, and an element 5 of thermo-sensitive material insulated electrically from the associated heating element 4 but subjected to the variations in the temperature of this element. Each of the thermo-sensitive elements 5 is of some material which has the characteristic of decreasing its electrical resistance in response to increases in the temperature of this element. Thermo-sensitive relay T is con- 100 105

trolled over a circuit which may be traced from terminal B, through back contact 17 of track relay R' , wire 18, back contact 19 of stick relay Q^F , wire 20, heater 4 of thermo-sensitive relay T , and back to terminal C. Thermo-sensitive relay T controls an auxiliary relay U over a circuit which passes from terminal B, through back contact 17 of track relay R' , wire 18, back contact 19 of stick relay Q^F , wires 20 and 21, thermo-sensitive element 5 of relay T , wire 22, winding of auxiliary relay U and back to terminal C. The parts are so proportioned that when heating element 4 of relay T is de-energized, the resistance of thermo-sensitive element 5 of relay T is so great that the current then flowing through relay U is not of sufficient magnitude to energize the latter relay. When the circuit is closed, however, for heating element 4, the resulting increase in the temperature of thermo-sensitive element 5 so decreases the resistance of this element that the current then flowing through relay U energizes this relay. Relay T is so constructed that a considerable interval of time elapses after the circuit is closed for the heating element 4 before the resistance of thermo-sensitive element 5 is sufficiently decreased to allow relay U to become energized. It follows that if relay Q^F is de-energized and relay R' becomes de-energized the circuit is immediately closed for heating element 4 of relay T but a considerable interval of time elapses before relay U becomes energized. The exact length of this time may be regulated to suit local conditions. Thermo-sensitive relay T^a is similar to relay T and has a similar time element. The heating circuit for relay T^a passes from terminal B, through back contact 23 of track relay R^a , wire 24, front contact 25 of relay U , wire 26, heating element 4 of relay T^a and back to terminal C. Wire 24 may also be connected with terminal B over back contact 28 of relay R^a or back contact 29 of relay R^a , and it follows that when relay U is energized the heating element of relay T^a will be supplied with current if one or more of relays R^a , R^5 and R^6 are de-energized. At the expiration of the time interval required for thermo-sensitive element 5 of relay T^a to sufficiently reduce its resistance, current flows from terminal B, through thermo-sensitive element 5 of relay T^a , wire 29^a, winding of a second auxiliary relay U^a , and back to terminal C. It is therefore plain that when a circuit is closed for relay T^a an interval of time elapses before relay U^a is energized. A directional relay V is provided with one pick up circuit which passes from terminal B, through front contact 30 of track relay R' , wires 31 and 32, front contact 33 of relay R^3 , wires 34, 34^a and 35, winding of relay V and back to terminal C. A sec-

ond pick up circuit is provided for relay V over which current flows from terminal B through back contact 36 of track relay R^3 , wires 37, 31, 38 and 39, front contact 40 of stick relay Q^E , wires 41, 34^a and 35, winding of relay V and back to terminal C. Current is at times supplied to relay V from a third pick up circuit which may be traced from terminal B through front contact 42 of stick relay Q^F , wires 43, 39, 38, 31 and 44, back contact 45 of track relay R' , wires 46, 34, 34^a and 35, winding of relay V and back to terminal C. Still another or fourth pick up circuit is provided for relay V over which current flows from terminal B, through front contact 137 of relay U^a , wires 38, 31 and 32, front contact 33 of relay R^3 , wires 34, 34^a and 35, winding of relay V and back to terminal C.

A fifth pick up circuit for relay V passes from terminal B, through back contact 36 of relay R^3 , wires 37, 31 and 44, back contact 45 of relay R' , wires 46, 34, 34^a and 35, winding of relay V , and back to terminal C. The sixth pick up circuit for this relay may be traced from terminal B, through front contact 30 of relay R' , wires 31, 38 and 39, front contact 40 of relay Q^E , wires 41, 34^a and 35, winding of relay V , and back to terminal C. A seventh pick up circuit is closed when relays R^3 and Q^F are both energized under which conditions current flows from terminal B, through front contact 42 of relay Q^F , wires 43, 39, 38, 31 and 32, front contact 33 of relay R^3 , wires 34, 34^a and 35, winding of relay V , and back to terminal C. Relay V is also provided with a stick circuit over which current flows from terminal B, through back contact 47 of repeating relay P^J , wires 48 and 50, front contact 51 of relay V , wires 52 and 35, winding of relay V and back to terminal C. Wire 50 may also be connected with terminal B by back contact 49 of signal repeating relay P^K . It follows that relay V , having been once energized, is maintained in its energized condition as long as either relay P^J or P^K is de-energized. The function and operation of relay V will appear as the description proceeds.

Each of the signals S normally indicates stop, but each is provided with an operating circuit which when closed causes the associated signal to display a proceed indication. The circuit for signal S^K passes from terminal B, through front contact 53 of track relay R^2 , wire 54, front contact 55 of track relay R^4 , wire 56, front contact 57 of track relay R^5 , wire 58, back contact 59 of track relay R^6 , wire 60, front contact 61 of signal repeating relay P^E , wire 62, front contact 63 of signal repeating relay P^F , wire 64, front contact 65 of signal repeating relay P^J , wire 66, back contact 67 of stick relay Q^J , wire 68, front contact 69 of relay V , wire

70, operating mechanism of signal S^k , and back to terminal C. The circuit for signal S^j passes from terminal B through front contact 71 of track relay R^2 , wire 72, back contact 73 of relay R^4 , wire 74, front contact 75 of track relay R^5 , wire 76, front contact 77 of relay R^6 , wire 78, front contact 79 of relay P^e , wire 80, front contact 81 of relay P^f , wire 82, front contact 83 of relay P^k , wire 84, back contact 85 of relay Q^k , wire 86, front contact 87 of relay V, wire 88, operating mechanism of signal S^j and back to terminal C. It should be particularly pointed out that the operating circuits for both signals S^k and S^j are carried over front contacts of directional relay V. The circuit for signal S^f may be traced from terminal B, through front contact 89 of track relay R' , wire 90, front contact 91 of track relay R^2 , wire 92, back contact 93 of track relay R^3 , wire 94, front contact 95 of track relay R^5 , wire 96, front contact 97 of relay P^e , wire 98, front contact 99 of relay P^j , wire 100, front contact 101 of relay P^k , wire 102, back contact 103 of stick relay Q^e , wire 104, operating mechanism of signal S^f and back to terminal C. The circuit for signal S^e may be traced from terminal B through back contact 105 of relay R' , wire 106, front contact 107 of relay R^2 , wire 108, front contact 109 of relay R^3 , wires 110 and 111, front contact 112 of relay R^4 , wire 113, front contact 114 of relay R^6 , wires 115 and 116, front contact 117 of relay R^5 , wire 118, front contact 119 of relay P^e , wire 120, front contact 121 of relay P^j , wire 122, front contact 123 of relay P^k , wire 124, back contact 125 of relay Q^f , wire 126, operating mechanism of signal S^e , and back to terminal C. The circuit just traced is provided with a branch which passes from wire 110, through wire 127, back contact 128 of relay U, and wire 129 back to wire 116. It is therefore clear that when relay U is de-energized, relays R^4 and R^6 are removed from the control of signal S^e .

As shown in the drawing all parts of the apparatus are in the positions corresponding to the normal or unoccupied condition of the track. Under these conditions all track relays R are energized and all signals S indicate stop. As a result all signal repeater relays P are energized and all stick relays Q are de-energized. Thermo-sensitive relays T and T^a are both de-energized, as are auxiliary relays U and U^a . Directional relay V is, however energized over front contacts 30 and 33 of track relays R' and R^3 , respectively.

In explaining the operation of the apparatus I will first assume that a northbound train moves over track b. As the train enters section H—J, track relay R^4 becomes de-energized, thus completing, at back contact 73 thereon, the operating circuit for sig-

nal S^j which signal thereupon displays a proceed indication. As soon as signal S^j moves away from the stop position circuit controller X^j opens, thus allowing relay P^j to become de-energized. This closes, at 70 back contact 130 of relay P^j , the pick up circuit for relay Q^j . At the same time, the closing of back contact 47 of relay P^j completes a stick circuit for relay V. As the train enters section J—K, track relay R^5 is 75 de-energized and the circuit for signal S^j is then opened at front contact 75 of relay R^5 . Signal S^j therefore goes to the stop position and returns relay P^j to its energized condition. Prior to this movement of signal S^j however, the closing of back contact 131 of relay R^5 completes a stick circuit for stick relay Q^j and this relay is now maintained in its energized condition over its own front contact, although its pick up circuit is open at back contact 130 of relay P^j which is now energized. When the train moves out of section H—J, relay R^4 becomes energized but this does not affect the apparatus. As the train enters section K—L, 80 relay R^6 is de-energized but signal S^k does not clear because the operating circuit of this signal is open at back contact 67 of stick relay Q^j . When the train leaves section J—K, track relay R^5 becomes energized but 85 stick relay Q^j is not de-energized, the stick circuit for this relay now being closed at back contact 132 of track relay R^6 . When the train leaves section K—L, the energization of relay R^6 causes the de-energization of 90 relay Q^j which returns the apparatus to its normal condition.

The operation of the apparatus as a southbound train traverses track b is similar to the operation of the apparatus when a northbound train moves over this track and will be readily understood from the foregoing.

I will next assume that an eastbound train moves over track a. As this train enters section D—E, the de-energization of relay R' completes the operating circuit for signal S^e which thereupon indicates proceed. At the same time the opening of front contact 30 of relay R' opens the circuit for 110 relay V which then becomes de-energized. Upon the clearing of signal S^e after the train enters section D—E, relay Q^e becomes energized and this relay is held in its energized condition until the train leaves section F—G as will be clear from the drawing. When the train moves out of section D—E the energization of relay R' completes the sixth pick up circuit for relay V 115 which therefore becomes energized. As the train moves into section F—G, a circuit is closed for relay V over front contact 40 of relay Q^e and back contact 36 of track relay R^3 . When the train moves out of section F—G, the energization of relay R^3 completes 120

the original circuit for relay V and relay Q^E becomes de-energized, thus returning the apparatus to the normal condition.

The operation of the apparatus as a west-bound train moves over track a will be understood without further explanation.

I will now assume that a train moving north on track b has entered section H—J. The clearing of signal S^J de-energizes relay P^J as explained hereinbefore. If, now, a westbound train on track a approaches crossing A, the de-energization of relay R³ as this latter train enters section F—G will not clear signal S^F, since the operating circuit for this signal is open at front contact 99 of repeater relay P^J which is now open. Signal S^F therefore remains at stop thus preventing the train on track a from proceeding past point F. As the train on track b proceeds past signal S^J, this signal goes to stop, thus re-energizing relay P^J, but the circuit for signal S^F is now open at front contact 95 of track relay R⁵ de-energized by the entrance of the northbound train into section J—K. When the northbound train clears section J—K, the energization of relay R⁵ completes the circuit for signal S^F and the train on track a is then allowed to proceed over the crossing. Similar protection is afforded to eastbound trains on track a when a northbound train is between points H and K and, also, trains in either direction over track a are prevented from proceeding over the crossing when a southbound train on track b is between points L and J.

In similar manner, if a train on track a is moving westward between points G and E or is moving eastward between points D and F, trains on track b are prevented from negotiating the crossing A.

It should be pointed out that if two trains one on track a and one on track b should approach the crossing and enter the approach sections such as sections L—K and F—G at approximately the same time, the de-energization of relay R³ by the train on track a would de-energize relay V, thus preventing signal S^K from clearing till the train on track a had passed point E. It will thus be seen that trains on track a have superiority, that is, if a train on track b and a train on track a approach crossing A at approximately the same time, the train on track b will be held by the corresponding signal till the train on track a has cleared the crossing. If the train on track b has however, caused relay P^K to be de-energized before the train on track a has entered section F—G, relay V will be maintained in its energized condition by a stick circuit over back contact of relay P^K. Signal S^K then will display a proceed indication and signal S^F will be held in the stop position.

It is clear from the drawing, that since

the operating circuit for each signal is controlled by all the track relays for the corresponding track, the signal for any train approaching the crossing will be held at stop if an opposing train on the same track is approaching the crossing from the other direction.

If however, an eastbound train occupies section D—E, a westbound train occupies section F—G, and section E—F is unoccupied, a train approaching the crossing on track b will be permitted to negotiate the crossing, since the simultaneous de-energization of relays R' and R³ by the trains occupying track a closes the fifth circuit for relay V thus permitting the operating circuit for signal S^J or S^K to be closed when the back contact of relay R⁴ or R⁶ is closed by a train approaching the crossing.

It is desirable to at times permit traffic moves on track b through the crossing A when a train occupies section D—E. For example, a train might be standing at the station Z, or using the siding W without endangering trains on track b. With my invention, the interlocking is automatically released for moves over track b after a train has occupied section D—E for a given time interval. I will assume a train to be standing at station Z or using siding W, or in some other way causing the de-energization of relay R'. As soon as such relay becomes de-energized, the closing of its back contact 17 causes the heating element 4 of thermo-sensitive relay T to be energized. After a considerable time interval the resistance of thermo-sensitive element 5 of relay T is so reduced as to allow current to flow therethrough to energize relay U. The opening of back contact 128 of relay U opens the branch around the front contacts of relays R⁴ and R⁶ in the control circuit for signal S^E. If now a train enters section H—J, the de-energization of relay R⁴ causes signal S^E to go to stop. At the same time a circuit is completed at back contact 23 of relay R⁴ and front contact 25 of relay U for the heating element of thermo-sensitive relay T^a. After a second considerable interval of time the resistance of thermo-sensitive element 5 of relay T^a is so reduced that relay U^a becomes energized. The closing of front contact 137 on this relay completes the fourth pick up circuit for relay V thus closing the circuit for signal S^J. The operation of the apparatus as this train proceeds through the track b or for a southbound train over track b will be readily understood without further explanation.

Since thermo-sensitive relay T requires a considerable interval of time for its operation, a train moving from left to right on track a will ordinarily enter section E—F before relay U becomes energized. This time interval required for the operation of

relay T and the similar time interval required for relay T_a prevent conflicting trains from simultaneously approaching the crossing A, but permit trains to move over track 5 b in either direction when a train stands in section D—E.

Although I have herein shown and described only one form of automatic interlocking apparatus embodying my invention, 10 it is understood that various changes and modifications may be made therein within the scope of the appended claims without departing from the spirit and scope of my invention.

15 Having thus described my invention, what I claim is:

1. In combination, a stretch of railway track, a second track intersecting said first track, means so controlled as to prevent 20 trains on said second track from proceeding past said intersection when a train is occupying said stretch, and means effective at the expiration of a time interval following the entrance of a train into said stretch to modify the control of said first means.

2. In combination, a stretch of railway track, a second track intersecting said first track, means effective when a train occupies 30 said stretch for preventing traffic movements past the crossing over said second track, and means effective at the expiration of a fixed time interval following the entrance of a train into said section for at times allowing traffic through the crossing over said second track.

3. In combination, a stretch of railway track comprising an insulated section, a second railway track intersecting said stretch adjacent said section, means for 40 automatically preventing traffic movements over said intersection on the second track when a train occupies said stretch, and means effective at the expiration of a time interval following the entrance of a train into said section for allowing such movements of traffic over said second track.

4. In combination, two intersecting railway tracks, means for each track for preventing 50 trains from approaching the intersection over such track when a train on the other track is on or near the intersection, and means for permitting movements over one track when a train is standing still on the other track adjacent the intersection.

5. In combination, two intersecting railway tracks, means for each track for preventing 55 trains from approaching the intersection over such track when a train on the other track is on or near the intersection, and means including a thermo-sensitive relay for at times permitting movements over one track when a train is standing still on the other track adjacent the intersection.

6. In combination, two intersecting railway tracks, a signal for governing traffic 60

approaching the intersection over one track and arranged to indicate proceed when a train approaches said signal, means for preventing said signal from indicating proceed if a train is approaching said intersection over said second track, and means for allowing said signal to indicate proceed if a train is standing still on said second track adjacent the intersection. 70

7. In combination, two intersecting railway tracks, a signal for governing traffic approaching the intersection over one track and arranged to indicate proceed when a train approaches said signal, means for preventing said signal from indicating proceed if a train is approaching said intersection over said second track, and means including 80 a time element relay for allowing said signal to indicate proceed if a train is standing still on said second track adjacent the intersection. 85

8. In combination, two intersecting railway tracks, a contact arranged to be operated when a train approaches the intersection over one track, traffic governing apparatus for the second track controlled by said contact, and means set into operation when said contact is operated and effective at the expiration of a time interval to remove said contact from the control of said traffic governing means. 90

9. In combination, two intersecting railway tracks, a contact arranged to be operated when a train approaches the intersection over one track, traffic governing apparatus for the second track controlled by said contact, and means including a time element relay for at times removing said contact from the control of said traffic governing means. 100

10. In combination, two intersecting railway tracks, a contact arranged to be operated when a train approaches the intersection over one track, traffic governing apparatus for the second track controlled by said contact, and means including a time element relay set into operation when said contact is operated and effective at the expiration of a time interval to remove said contact from the control of said traffic governing means. 110

11. In combination, two intersecting railway tracks, a contact arranged to be operated when a train approaches the intersection over one track, traffic governing apparatus for the second track controlled by said contact, means set into operation when said contact is operated and effective at the expiration of a time interval to remove said contact from the control of said traffic governing means, and means for operating said traffic governing means when a train on said second track approaches the intersection. 120

12. In combination, two intersecting railway tracks, a contact arranged to be oper- 130

- ated when a train approaches the intersection over one track, traffic governing apparatus for the second track controlled by said contact, means including a time element relay for at times removing said contact from the control of said traffic governing means, and means for operating said traffic governing means when a train on said second track approaches the intersection.
13. In combination, two intersecting railway tracks, a contact arranged to be operated when a train approaches the intersection over one track, traffic governing apparatus for the second track controlled by said contact, means for at times removing said contact from the control of said traffic governing means, and means arranged to be set into operation by a train approaching the crossing on the second track when said contact is removed from the control of the traffic governing means and effective at the expiration of a time interval to operate said traffic governing means.
14. In combination, two intersecting railway tracks, a relay arranged to be de-energized when a train approaches the intersection over one track, means set into operation when said relay is de-energized and effective at the expiration of a time interval for again energizing said relay, and traffic governing means for the second track controlled by said relay.
15. In combination, two intersecting railway tracks, a relay arranged to be de-energized when a train approaches the intersection over one track, means set into operation when said relay is de-energized and effective at the expiration of a time interval for again energizing said relay, and means for preventing traffic from passing over said intersection on the second track when said relay is de-energized.
16. In combination, two intersecting railway tracks, a relay arranged to be de-energized when a train approaches the intersection over one track, means for again energizing said relay at the expiration of a time interval, and traffic governing means for the second track controlled by said relay.
17. In combination, two intersecting railway tracks, a relay arranged to be de-energized when a train approaches the intersection over one track, means including a time element relay for again energizing said relay at the expiration of a time interval, and traffic governing means for the second track controlled by said relay.
18. In combination, two intersecting railway tracks, a relay arranged to be de-energized when a train approaches the intersection over one track, means set into operation when a train approaches the intersection over the second track and effective at the expiration of a time interval for again energizing said relay, and traffic governing means for the second track controlled by said relay.
- means for the second track controlled by said relay.
19. In combination, two intersecting railway tracks, a track relay for one track arranged to be de-energized when a train approaches the intersection over such track, an auxiliary relay arranged to be energized at the expiration of a time interval following de-energization of said track relay, and traffic governing means for the second track controlled by said auxiliary relay.
20. In combination, two intersecting railway tracks, a track relay for one track arranged to be de-energized when a train approaches the intersection over such track, a slow acting relay controlled by said track relay, and traffic governing means for the second track controlled by said slow acting relay.
21. In combination, two intersecting railway tracks, a track relay for one track arranged to be de-energized when a train approaches the intersection over such track, a slow acting relay controlled by said track relay, an auxiliary relay controlled by said slow acting relay, and traffic governing means for the second track controlled by said auxiliary relay.
22. In combination, two intersecting railway tracks, a track relay for one track arranged to be de-energized when a train approaches the intersection over such track, a slow acting relay controlled by said track relay, a second track relay for said second track arranged to be de-energized when a train approaches the intersection over such second track, an auxiliary relay controlled by said relay and by said second track relay, and traffic governing means for said second track controlled by said auxiliary relay.
23. In combination, two intersecting railway tracks, a track relay for one track arranged to be de-energized when a train approaches the intersection over such track, a time element relay controlled by said track relay, and traffic governing means for each said track controlled by said time element relay.
24. In combination, two intersecting railway tracks, a track relay for one track arranged to be de-energized when a train approaches the intersection over such track, a slow acting relay controlled by said track relay, traffic governing means for the first said track controlled by said slow acting relay, a second slow acting relay controlled by the first said slow acting relay, and traffic governing means for the second track controlled by said second slow acting relay.
25. In combination, two intersecting railway tracks, a track relay for one track arranged to be de-energized when a train approaches the intersection over such track, a thermo-sensitive relay controlled by said track relay, an auxiliary relay arranged to

be energized at the expiration of a time interval following the energization of said thermo-sensitive relay, a second track relay for said second track and arranged to be de-
 5 energized when a train approaches said crossing over such second track, traffic governing means for said first track controlled by said second track relay and by said auxiliary relay, a second thermo-sensitive relay con-
 10 trolled by said auxiliary relay, a second auxiliary relay controlled by said second thermo-
 sensitive relay, a directional relay controlled by said first track relay and by said second auxiliary relay, and traffic governing means
 15 for said second track controlled by said directional relay.

26. In combination, two intersecting rail-
 way tracks, a stick relay arranged to be energized when a train approaches the in-
 20 tersection moving in one direction along the
 first track, a track relay arranged to be de-
 energized as such train recedes from the in-
 tersection, a directional relay controlled by
 25 said stick relay and by said track relay, and
 traffic governing means for the second track
 controlled by said directional relay.

27. In combination, two intersecting rail-
 way tracks, a stick relay arranged to be en-
 30 ergized when a train approaches the inter-
 section moving in one direction along the
 first track, a track relay arranged to be de-
 energized as such train recedes from the in-
 35 tersection, a directional relay controlled by
 said stick relay and by said track relay,
 traffic governing means for the second track
 controlled by said directional relay, and
 means operated by said traffic governing
 40 means for modifying the control of said di-
 rectional relay.

40 28. In combination, two intersecting rail-
 way tracks, a stick relay arranged to be en-
 ergized when a train approaches the inter-
 section moving in one direction along the
 first track, a track relay arranged to be de-
 45 energized as such train recedes from the in-
 tersection, an auxiliary relay controlled by
 said track relay; a directional relay con-
 trolled by said auxiliary relay, said stick
 relay and said track relay; and traffic gov-
 50 erning means for the second track controlled
 by said directional relay.

29. In combination, two intersecting rail-
 way tracks, a stick relay arranged to be en-
 ergized when a train approaches the inter-
 section moving in one direction along the
 55 first track, a track relay arranged to be de-
 energized as such train recedes from the in-
 tersection, a second track relay arranged to
 be de-energized when a train moving in the
 opposite direction over said first track ap-
 60 proaches the crossing, slow acting means
 controlled by said second track relay, an
 auxiliary relay controlled by such slow act-
 ing means; a directional relay controlled
 by said stick relay, said first track relay and
 65 said auxiliary relay; and traffic governing
 means for the second track controlled by
 said directional relay.

30. In combination, two intersecting rail-
 way tracks, signals for said tracks inter-
 70 controlled to prevent two trains on said two
 tracks respectively from meeting at the in-
 tersection, and slow acting means set into
 operation when a train on one track ap-
 proaches said intersection for releasing the
 75 signals for the other track after a given
 interval of time.

31. In combination, two intersecting rail-
 way tracks, signals for said tracks inter-
 controlled to prevent two trains on said two
 80 tracks respectively from meeting at the in-
 tersection, an electrically isolated section in
 one of said tracks on one side of said inter-
 section, and slow acting means set into op-
 eration when a train approaching said in-
 85 tersection enters said section for releasing
 the signals for the other track if such train
 remains in said section for more than a
 given interval of time.

32. In combination, two intersecting rail-
 way tracks, signals for said tracks inter-
 controlled to prevent two trains on said two
 tracks respectively from meeting at the in-
 tersection, and slow acting means set into
 90 operation when a train approaching said
 intersection on one track enters a given por-
 tion of such track for releasing the signals
 for the other track if the train consumes
 more than a given amount of time in passing
 95 through said portion of track.

In testimony whereof I affix my signature.
 LESTER E. SPRAY.
